L. FRITSCH

SUSPENSORY

Filed July 23, 1921

Inventor
Lewis Fritsch
By Walter D. Murray
Attorney

UNITED STATES PATENT OFFICE.

LEWIS FRITSCH, OF CINCINNATI, OHIO.

SUSPENSORY.

Application filed July 23, 1921. Serial No. 487,007.

To all whom it may concern:

Be it known that I, LEWIS FRITSCH, a citizen of the United States of America, and a resident of Cincinnati, in the county of 5 Hamilton and State of Ohio, have invented a new and useful Improvement in a Suspensory, of which the following is a specification.

An object of my invention is to provide 10 washable suspensory of the type shown in the accompanying drawings, wherein the use of metal parts and the consequent rusting thereof are eliminated.

Another object is to provide suspensory 15 wherein the parts of the device can be readily and easily disassociated so as not to subject to the water, those parts that are injuriously affected by water.

Another object is to provide a device that 20 is readily adjustable and wherein the adjustable parts serve the additional function of retaining the device upon the wearer.

Another object is to eliminate several of 25 the steps which up to this time have been resorted to in the manufacture of such devices.

These and other objects are attained by 30 the means described herein and disclosed in the accompanying drawings, in which—

Fig. 1 is a perspective view of a device 35 embodying my invention.

Fig. 2 is an enlarged sectional view on line 2—2 of Fig. 1.

The pouch a is made of some washable 35 material or fabric and has its upper edge turned down upon and hemmed upon itself, whereby a loop or way a' is formed along its upper edge or waist band, through which way removably extends the flat leather strap 40 a^2 having an elongated slot a^3 in one end thereof and a perforation a^4 in its other end. The perforation a^4 is of such size that the head a^5 of the bone button a^6 may be inserted therethrough. The slot a^3 is made 45 of a length substantially equal to the width of the single strip of elastic webbing a^7 extending therethrough. The elastic webbing has a series of slits or button holes a^8 formed in its ends, through which the head 50 of the button a^6 may be inserted. The pouch has mounted upon its lower extremity a loop a^9 of tape or other suitable material, having the same sides of its opposite ends secured upon opposite sides of the fabric. The tape 55 loop a^9 therefore will lie flat and have its

surfaces in substantial alignment with the surfaces of the pouch. One portion of the elastic webbing strip a^7 forms a waist band extending between the opposite ends of the leather strap a^2 and the other portion of the webbing forms a retaining member for the lower end of the pouch, and extends between the ends of the leather strap, assuming a position over the lower portion of the buttock of the wearer and extending through 60 the tape loop a^9 .

The device is assembled in the following manner. The head of the button a^6 is inserted in one end of the webbing and is then inserted in the perforation in the leather 70 strap. The strap is threaded through the way formed along the upper end of the pouch and the free end of the webbing is threaded through the tape loop and through the elongated slot in the leather strap, and 75 said end is then secured upon the button by inserting the head of such button through one of the slits in the elastic webbing. The button is inserted in the appropriate slot to give the webbing the proper length to cause 80 the wearer no inconvenience. The length of the two portions of the webbing can be readily adjusted by threading same through the elongated slot in the leather belt and by passing the button through the slits giving 85 the proper adjustments to the webbing.

What I claim is:

1. An article of suspensory comprising a pouch having a waist band having a slot at one of its ends, a loop extending from the 90 lower end of the pouch, and webbing extending through the slot in the waist band and through the loop and having its ends secured upon the opposite end of the waist band. 95

2. An article of suspensory comprising a pouch having a waist band, the ends of which are slotted, a loop extending from the lower end of the pouch, webbing extending through one of the slots in the waist band and through the loop, and a button extending through the other slot in the waist band and upon which the ends of the webbing are mounted. 100

3. An article of suspensory comprising a pouch having loops formed at its upper and lower ends, a strap extending through the loop formed at the upper end of the pouch and having a slot in one of its ends, and webbing extending through the slot in 110

the strap and through the loop at the lower end of the pouch and having its ends mounted upon the other end of the strap.

4. An article of suspensory comprising a pouch having loops formed at its upper and lower ends, a strap extending through the loop formed at the upper end of the pouch and having slots formed in its ends, a button extending through one of the slots, and

webbing having its ends mounted upon the button and being threaded through the other perforation in the strap and through the loop at the lower end of the pouch.

In testimony whereof, I have hereunto subscribed my name this 20th day of July, 1921.

LEWIS FRITSCH.
